UNITED STATES PATENT OFFICE.

WILLIAM ARTHUR, OF NEW HAVEN, CONNECTICUT.

COASTING-REGISTER.

1,319,452.

Specification of Letters Patent.

Patented Oct. 21, 1919.

Application filed March 19, 1918, Serial No. 223,337. Renewed March 13, 1919. Serial No. 282,491.

To all whom it may concern:

Be it known that I, WILLIAM ARTHUR, a subject of the King of England, residing at New Haven, in the county of New Haven 5 and State of Connecticut, have invented certain new and useful Improvements in Coasting-Registers, of which the following is a specification.

This invention relates to certain new and 10 useful improvements in coasting registers, and pertains more particularly to a register employed for the purpose of positively registering the coasting periods, and for also enabling the power on, braking, and stopping 15 periods to be ascertained or readily computed, to thus enable the efficiency of the conductor as well as the motorman to be ascertained.

The present invention proposes to provide 20 a coasting register which is active only during coasting, and which is rendered quiescent during the periods of braking, power on and stopping, so that the coasting record of the motorman alone can be accordingly 25 determined, or by deducting the coasting record so obtained from the total time of the run, the sum of the braking, power on and stopping periods can be both easily and readily ascertained.

30 The motorman must complete his run in a certain prescribed time, but if the conductor wastes time by taking too long in opening and closing the door, or in not promptly giving the ahead signal when the 35 passengers have been either let off or taken on, then the motorman must speed his car up in order to complete the run in the scheduled time. This deprives the motor of the opportunity of coasting and also requires a 40 longer time of brake application, with the result that more current is employed, and the equipment is subjected to greater wear and tear. The increased consumption of power necessarily requires a corresponding 45 increase in coal consumption.

The present invention therefore briefly proposes to provide a register which indicates the efficiency of the motorman alone, or of both the motorman and the conductor, or 50 in other words of the crew as distinguished

from prior devices which propose to indicate the efficiency of the motorman alone.

Further and other objects will be later herein set forth and manifested in the course of the following specification.

55

In the drawings:

Figure 1 is a side elevation of the invention; showing the same in a case with its front removed;

Fig. 2, is a top plan view, the case being 60 shown in section;

Fig. 3, is a section on line 3—3 of Fig. 2; and

Figs. 4, 5 and 6 are fragmentary side elevations, partly in section, showing the parts 65 during their various stages of operation.

In proceeding in accordance with the invention, a suitable clock mechanism 1, is employed, the master gear 2 of which operates a pinion 3 mounted on a shaft 4, the latter 70 being in suitable operative connection with a coasting register 5 which, as hereinafter explained enables the sum of the braking period, the power on period and the stop period to be ascertained.

75 A pipe 6 leads from the air brake line and has a cylinder 7 connected thereto within which latter is a plunger 8 having a rod 9 connected thereto. Rod 9 has a pin 10 at its upper end which engages in the slot 11 of an 80 arm 12, the latter mounted on a suitable shaft 13. A second arm 14 is also secured to the shaft 13 and carries a light curved leaf spring braking and starting member 15, which latter engages a brake wheel 16 85 mounted on the balance wheel arbor 17 of the clock works.

The plunger 9 also has an arm 18 rigidly secured thereto, the arm carrying a pin 19 at its outer end, which pin extends through a 90 slot 20 formed in an arm 21 mounted on the shaft 22, of a register 23, the latter indicating the number of times the brake is operated, by registering each time the brake is operated.

95 An electro-magnet 24 is suitably connected as indicated at W, in the circuit S, of the usual motor controller C, so that whenever the motor controller is operated to close the circuit the magnet will be energized. A 100

hinged arm 25 carries an armature 26 which latter is attracted upon energization of the magnet, the free end of the arm being disposed so as to be capable of engaging beneath the arm 18 of the plunger rod 9 as shown in Fig. 6. A finger 27 is rigidly secured to the arm 25 and extends upwardly therefrom.

The clock is normally wound and is active during coasting, the parts in this position being indicated in Fig. 3, in which the spring brake 15 is free of engagement with the brake wheel 16 of the clock works, the plunger being also in its lowermost position. When the brakes are applied, air entering the cylinder 7 will move the plunger to its uppermost position as depicted in Fig. 4, thereby raising arm 18, and the latter through the pin 19, slot 20 and arm 21 will rotate the shaft 22 of the brake register 23 and register a time of brake applied, on said register.

This upward movement of the plunger causes the spring 15 to move upwardly to the position of Fig. 4, engaging or braking the wheel 16 so as to cause the clock to stop.

The clock is thus caused to remain quiescent throughout the braking period. When the brakes are released the plunger drops but is caught by the finger 27, and prevented from completing its down movement, being held in the position shown in Fig. 5, so that the register will continue to remain quiescent throughout the time during which the car stops or remains at a standstill.

When the motor is started the brakes being off, and the parts in the position of Fig. 3, the magnet 24 is energized, attracting the armature 26, and moving the parts to the position of Fig. 6, in which position the spring 15 has caused the clock to still remain stopped thereby continuing stoppage of the coasting register 5, so that as long as the current remains on the register 5 will remain quiescent. This upward movement of the rod 9 is however not sufficient to operate the brake register 23 so that the latter is consequently not affected.

When the current is shut off and the brakes are off, with the parts in the position of Fig. 6, the arm 25 will be released, due to the deenergization of the magnet 24, and the plunger then completes its down movement, bringing the parts to the position of Fig. 3, in which the coasting register is rendered active to positively register actual coasting.

It will thus be apparent from the foregoing that whenever the brakes are applied the brake register 23 will be operated once to indicate a time of brake's operation. As long as the brakes are kept applied the upper or coasting register 5 will remain quiescent because the plunger is kept in its uppermost position of Fig. 4, and as long as the car

remains at a stop the register 5 will remain quiescent because, upon release of the brakes the plunger is prevented from completing its down movement to start the clock, due to the parts being then in the position of Fig. 5, the current being off. When the current is on the upper register 5, will also remain quiescent throughout the length of time the current is kept on, since the plunger will be held in the position of Fig. 6, in which the clock is braked and rendered inactive. However, as soon as the current is shut off and the brakes are released, then the parts will occupy the position of Fig. 3, in which the clock is active, and the coasting or upper register 5, is likewise rendered active to positively indicate the coasting period.

The finger 27 is preferably secured to the arm 25 so as to be readily removable therefrom, so that if desired, the apparatus will register power on and braking to the exclusion of stopping. To enable power on only to be registered, a valve 30 is placed in pipe 6, so as to allow the air to be cut off from the cylinder, and to enable the braking period alone to be determined it is merely necessary to remove the armature carrying arm 25.

What is claimed is:

1. In a coasting register, a register mechanism active during coasting, means including a movable element controlled by the motor controller to move said element to one position for rendering said mechanism inactive when the power is on, means controlled by the brake controller to move said element to a second position for rendering said mechanism inactive during the braking periods, and means to cause said element to assume a third position to render said mechanism inactive during the stopping periods.

2. In a coasting register, a register mechanism active during coasting, a plunger controlled by the brake controller and having means for rendering said mechanism inactive whenever the brakes are applied, means controlled by the motor controller for operating said plunger and its said means be caused to assume a third position to render the register mechanism inactive whenever the power is applied, and means whereby when the brakes are released following operation thereof said means of the plunger will render said mechanism inactive.

3. In a coasting register, a register mechanism active during coasting, an actuator controlled by the brake controller and having means for rendering said mechanism inactive whenever the brakes are applied, means controlled by the motor controller for operating said actuator and its said means be caused to assume a third position to render the register mechanism inactive when-

ever the power is applied, and means whereby when the power is applied following application of the brakes said means of the actuator will render the register mechanism inactive.

4. In a coasting register, a register mechanism active during coasting; an element having means for rendering said mechanism inactive, means controlled by the brake controller for actuating said element to cause the element to assume a position to render said mechanism inactive whenever the brakes are applied, means for holding said element in a second position to cause its means to render said mechanism inactive as long as the car is stopped, and means controlled by the motor controller for operating said element to cause said means thereof to assume a third position to render the register mechanism inactive when the power is applied following application of the brakes, and for enabling said element to move to a fourth position causing its said means to render the register mechanism active when the power is applied and the brakes are off.

5. A registering mechanism for determining the efficiency of electric train crews, including a register for indicating each time the brake is operated, mechanical means for operating said register from the air brake controller, a coasting register inactive during the power on, stopping and braking periods, and means to actuate said mechanical means for rendering the coasting register inactive controlled by the motor controller and by the brake controller.

6. In a register mechanism for determining the efficiency of motormen, a brake register, means controlled by the brake controller for actuating said register upon each application of the brakes including a plunger, a coasting register, clock mechanism to actuate said coasting register, means associated with the plunger for holding said clock mechanism inactive when the brakes are applied, means for holding the plunger following release of the brakes in a second position to cause the said means thereof to render the clock mechanism inactive, and means controlled by the motor controller for releasing the plunger to render the clock mechanism active when the power is shut off.

7. In a register mechanism for determining the efficiency of motormen, a brake register, means controlled by the brake controller for actuating said register upon each application of the brakes including a plunger, a coasting register, clock mechanism to actuate said coasting register, means associated with the plunger for holding said clock mechanism inactive when the brakes are applied, an electro-magnet controlled by the motor controller, means operable

upon energization of the magnet for moving the plunger to a second position to cause its said means to hold the clock mechanism inactive and to the exclusion of operation of the brake register, and means associated with said magnet operated means for holding the plunger in a third position to render the clock mechanism inactive when the brakes are released and the power is off.

8. In combination with a brake register, and a normally active combined register for registering power on and braking periods, means common to each register and controlled by the brake controller for operating the brake register and rendering the combined register quiescent when the brakes are applied, and means controlled by the motor controller for operating said common means to render the combined register inactive to the exclusion of operating the brake register when the power is applied.

9. In combination with a brake register, and a normally active combined register for indicating power on and braking periods, means controlled by the brake controller for operating the brake register and maintaining the combined register inactive whenever the brakes are applied, and means controlled by the motor controller for maintaining the combined register inactive to the exclusion of the brake register whenever power is applied.

10. In combination with a brake register, and a normally active combined register for indicating power on and braking periods, means to operate the brake register when the brakes are applied and to maintain the combined register inactive, and means to operate the first means to render the combined register inactive and to the exclusion of operation of the brake register when the power is applied.

11. In a coasting register, a register mechanism active during coasting, a plunger, means borne by the plunger for rendering said mechanism inactive, means controlled by the brake controller for actuating the plunger to cause the plunger means to render said mechanism inactive when the brakes are applied, an abutment on the plunger, an element controlled by the electro-magnet to engage said abutment to lift the plunger to cause said means of the plunger to render said mechanism inactive when the power is on, and means borne by said element to engage said abutment to hold the plunger in a position to render said mechanism inactive when the brakes are released following application of the latter.

12. In a coasting register, a register mechanism active during coasting, a plunger, means borne by the plunger for rendering said mechanism inactive, means con-

trolled by the brake controller for actuating the plunger to cause the plunger means to render said mechanism inactive when the brakes are applied, an electro-magnet, means controlled by the electro-magnet and engaging said plunger for actuating the latter to cause the plunger means to render said mechanism inactive when the power is on and means engaging said plunger to

hold same in a position to cause said plunger means to render said mechanism inactive when the brakes are released, following application of the latter to register the time throughout which the car remains at a standstill. 10
